UNITED STATES PATENT OFFICE.

JOHN F. DAPRIX, OF UTICA, NEW YORK.

CHANNELING DEVICE FOR SEWING-MACHINES.

1,194,719.

Specification of Letters Patent. Patented Aug. 15, 1916.

Application filed December 17, 1914. Serial No. 877,662.

To all whom it may concern:

Be it known that I, JOHN F. DAPRIX, of Utica, in the county of Oneida and State of New York, have invented certain new and useful Improvements in Channeling Devices for Sewing-Machines; and I do hereby declare that the following is a full, clear, and exact description thereof, which will enable others skilled in the art to which it applies to make and use the same, reference being had to the accompanying drawings, and to the reference-numerals marked thereon, which form part of this specification.

My present invention relates to shoe-channeling devices such as are used upon sewing machines for sewing shoes and other forms of leather goods or similar material.

The purpose of my invention is to provide an improved device of the character described and one which is simple and economical of construction, easily applied to or removed from sewing machines and efficient and durable in operation.

A further purpose of my invention is to provide a channeling device of the character described having improved means for cutting a channel of varying depth at different times and having improved means for readily adjusting the depth of such channel without changing the channeling knife or the position of the knife or without removing the device from the work-plate of the sewing machine.

A still further purpose of my invention is to provide a channeling device wherein the depth of the channel is regulated not by changing the position of the channeling knife but by raising or lowering the top plate of the device so as to leave a greater or less extent of channeling knife above the top plate and so effective for work. Improved means are also provided for supporting this top plate in varying positions effectively against the considerable pressure and strain brought thereupon during the sewing operation.

Figure 1 is a top or plan view of a channeling device embodying my invention. Fig. 2 is a top or plan view thereof with the top plate removed. Fig. 3 is a side elevation of the device shown in Fig. 1, with the top plate slightly raised. Fig. 4 is a cross-section on line 4-4 of Fig. 1 but with the wedge member moved inward and the top plate accordingly raised. Fig. 5 is a plan view of the top plate. Fig. 6 is a bottom

view of the device shown in Fig. 1. Fig. 7 is a side elevation of the wedge shaped member used to raise the top plate. Fig. 8 is a side view of a modified form of wedge shaped member. Fig. 9 is a vertical cross-sectional view on lines 9-9 of Fig. 1 or Fig. 4 but on a considerably enlarged scale.

Referring to the drawings in a more particular description, there is shown a base 12 of proper size and adapted to rest in any desired position upon the work bed 13 of a sewing machine and provided with a needle-receiving aperture 14 adapted to receive therethrough the usual sewing machine 70 needle 15 and awl 16 of the leather or shoe sewing machine upon which the device is to be used. To the base 12 is also secured the channeling knife 17 which is illustrated in the drawings as being let into the bottom of 75 the base 12 and having its cutting end at right angles to its fastened portion and extended up through the needle aperture 14. Preferably also the channeling knife 17 will be removably and adjustably secured to the 80 base 12 as by set screw 18 of which the head bears against the upper surface of base 12 while its screw-threaded portion extends loosely through an elongated slot 19 in the base portion and there is screw-threaded into 85 the shank portion 17a of the knife. By loosening the set screw 18 the knife 17 may be adjusted longitudinally of the length of its shank in its containing groove 20 in the 90 bottom of the base 12 so that the channeling 95 knife 17 may be properly positioned relative to the needle 15 and awl 16 of the sewing machine. Across the top of the base 12 a little inwardly from its sides are provided two grooves 21 in which are slidingly mounted wedges 22 having their ends away from the knife united by loop 22a so that the two 100 acting wedges are really one wedge-shaped member with the loop 22a adapted to be used as a convenient handle projecting out from 105 the end of the device away from the knife 17. Over the base 12 fits a top plate 23 similar in size and shape to the base 12 and also provided with a similarly located knife and needle aperture 24. It will be obvious 110 that as the wedge-shaped member 22 is moved inward from its position shown in Figs. 1, 2 and 3 the blades of the member 22 being wedge-shaped as shown in side elevation will elevate the top plate 23 and cause particularly its outer end near the knife to move upward. It will be obvious that this

upward movement of the knife end of the top plate will operate in effect to sheath or house the relatively permanently fixed knife 17 so that less of the knife will extend above the top plate 23 and accordingly a shallower channel will be cut in the sole of the shoe being sewed by the machine. It will be further obvious that by proper proportioning of the parts the knife may be entirely housed when needed by sufficiently extending the wedge or may be brought into operation by withdrawing the same.

Proper means will be provided for keeping the top plate 23 in crosswise and longitudinal alignment with the lower member no matter how far up the top plate is moved. As such positioning means I extend the outer end of the top plate 23 inwardly and turn it down by the inner end of the base 12 in the form of clip 25. Furthermore I provide upstanding pins 26 toward the inner end of the base projecting snugly into holes 27 in the top plate 23. A screw-threaded pin 28 projecting upwardly from the base 12 through an aperture 29 in the top plate 23 receives a thumb nut 30 whereby the operator may securely hold the top plate in position down against the wedge shaped member after the adjustment has once been made. An elongated aperture 31 is provided in the top plate 23 over set screw 18 to allow of the adjustment of knife 17 without removing top plate 23. Holes 32 are provided in the base 12 for securing the device to the work bed of a sewing machine by means of screws 35. Downwardly projecting lugs 33 may be provided upon the base 12 fitting into sockets 34 upon the work bed of the sewing machine to assist in readily placing and securely holding the device in proper position.

In operation it will be seen that this device does not have to be removed from the work bed of the machine in order to adjust the depth of the channel from deep to shallow or vice versa or from some channel to no channel at all or vice versa, but that the operator simply loosens thumb nut 30 and pushes in or pulls out the wedge shaped member 22 by means of its loop portion 22^a until there is the proper amount of knife or absence of knife above the top plate 23, then the thumb nut 30 is screwed down against the top plate firmly holding it in desired position.

It will thus be seen that I have provided a channeling device very well adapted to be adjusted to various depths of channel or absence of channel without removing any part

of the device and without removing the device from the sewing machine and furthermore without moving or changing the channeling knife itself. With many forms of channeling device heretofore used one or more of these changes have been necessary, requiring several or a good many minutes to effect the change resulting in great loss of time and waste of efficiency upon the machine.

What I claim as new and desire to secure by Letters Patent is:

1. In a channeling device for sewing machines, the combination of a base having a needle aperture and adapted to rest upon the work bed of a sewing machine, a channeling knife extending upward from said base, a top plate over the base provided with a needle and knife aperture and a wedge shaped member interposed between the base and the top plate and adapted to support the latter at varying positions above the base by longitudinal adjustment of said wedge.

2. In a channeling device for sewing machines, the combination of a base having a needle aperture and adapted to rest upon the work bed of a sewing machine, a channeling knife extending upward from said base, a top plate over the base provided with a needle and knife aperture, a wedge shaped member interposed between the base and the top plate and adapted to support the latter at varying positions above the base by longitudinal adjustment of said wedge and adjustable means for holding said top plate down upon the wedge.

3. In a channeling device for sewing machines, the combination of a base having a needle aperture and adapted to rest upon the work bed of a sewing machine, a channeling knife extending upward from said base, a top plate over the base provided with a needle and knife aperture and a two-armed wedge-shaped member interposed between the base and the top plate and adapted to support the latter at varying positions by longitudinal movement of said wedge-shaped member, said wedge-shaped member having its outer ends connected by a loop forming a handle for adjustment of said member.

In witness whereof I have affixed my signature, in the presence of two witnesses, this 24th day of Nov. 1914.

JOHN F. DAPRIX.
